UNITED STATES PATENT OFFICE.

JACOB L. WEBER, OF CHICAGO, ILLINOIS.

KNOCKDOWN CRATE OR BOX.

1,353,688.

Specification of Letters Patent. Patented Sept. 21, 1920.

Application filed January 19, 1920. Serial No. 352,283.

To all whom it may concern:

Be it known that I, JACOB L. WEBER, a citizen of the United States, and a resident of Chicago, in the county of Cook and State 5 of Illinois, have invented a new and useful Improvement in Knockdown Crates or Boxes, of which the following is a full, clear, and exact description.

My invention relates to improvements in 10 knock down crates, and it consists in the combinations, constructions and arrangements herein described and claimed.

An object of my invention is to provide a knock down or collapsible crate having 15 sides and a partition which may be swung parallel to the top and bottom when the crate is folded and which not only perform their obvious functions when the crate is set up but also maintain the same in its set 20 up or operative position.

A further object of my invention is to provide a device of the type described that is strong and durable in construction, light in weight, and which can be manufactured 25 cheaply.

A further object of my invention is to provide a device of the type described which can be set up or folded easily and quickly and which will occupy but a small space 30 when folded.

A further object of my invention is to provide a novel means of holding the device in its folded condition.

Other objects and advantages will appear 35 in the following specification, and the novel features of the invention will be particularly pointed out in the appended claims.

My invention is illustrated in the accompanying drawings, forming part of this application, in which—

Figure 1 is a top plan view of the device in set up or operative condition,

Fig. 2 is a side elevation of the same,

Fig. 3 is an end view of the device, the 45 dotted lines indicating a position assumed by a gate when opened,

Fig. 4 is a section along the line 4—4 of Fig. 1,

Fig. 5 is a section along the line 5—5 of 50 Fig. 1,

Fig. 6 is a side elevation of the device in its collapsed condition,

Fig. 7 is a section along the line 7—7 of Fig. 6,

55 Fig. 8 is a top view of a portion of a modified form of the device in extended position,

Fig. 9 is a top view of a portion of a modified form of the device in extended position.

In carrying out my invention in its pre-

ferred form, I provide similar end sections, 60 similar side sections, a top section, a bot-

tom section, a gate hingedly fastened to the top section, indicated in general at A, B, C, D, and E respectively, and a partition F.

The end sections A comprise upper portions 65 1 and lower portions 2 held together by

hinges 3. The top section C comprises a rectangular frame 4 to which side portions

5 and end portions 6 are secured. Slots 7 are cut in the frame 4, the slotted sides of

the frame 4 being covered and reinforced

by plates 8. Strips 9 are secured to the

under side of the frame 4 as illustrated in

Fig. 1 of the accompanying drawings. The

strips 9 strengthen the top section C and

provide a supporting base for the gate E

when the latter is in closed position. The

gate E comprises longitudinal slats 10 se-

cured to cross bars 11. The cross bars 11

have grooves 12 adapted to register with

the grooves 7 in the frame 4. Cover plates

13 are provided for the grooved portions of

cross bars 11. A removable closure 14,

which is preferably of the same width as the

slats 10 and of the same length as the top

section C, is slidably disposed within the

registering grooves 7 and 12 and thus main-

tains the gate in closed position against the

frame 4. A spring locking member 15 (see

Fig. 4) is secured to the under surface of

90 one of the cross bars 11 for a purpose to be

hereafter set forth. The closure 14 is with-

drawn from the grooves 7 and 12 to al-

low the gate E to be swung upwardly upon

its hinges 16 and the contents of the crate

95 removed. Or, a part of the contents of the

crate may be removed through the aperture

formed by removing the closure 14 without

opening the gate or disturbing the remain-

der of the contents of the crate.

100 The bottom section D is preferably formed

of a solid panel 17, upwardly extending side

portions 18, upwardly extending end por-

105 tions 19, and bottom cleats 20. The side sec-

tions B are fastened by hinges 21 to the side

105 portions 5 of the top section C and may be

swung downwardly against the upwardly

extending side portions 18 of the bottom sec-

110 tion D. The partition F is hingedly fas-

tened at 22 to the bottom section D (see Fig.

4) and may be swung upwardly until par-

115 allel with the end section A when the crate is

in operative position. The spring locking member 15 holds the partition F in this position and the partition F in turn maintains the side sections B in operative position and 5 also divides the crate into two compartments. The end sections A are fastened to the top section C and the bottom section D by hinges 23 as shown in Fig. 4 of the accompanying drawings.

10 From the foregoing description of the various parts of the device, the operation thereof may be readily understood. The crate is held in its knock down or collapsed condition as shown in Figs. 6 and 7 when 15 the closure 14 is inserted through U-shaped keepers 24 which are pivotally fastened at 25 to the bottom section D as shown in Fig. 7 so that they may be swung downwardly against the bottom D and out of the way.

20 It is to be understood that the closure 14 is at the same time disposed within the grooves 7 and 12 to hold the gate E in closed position. To put the crate in extended or operative position, the closure 14 is withdrawn in 25 the manner previously described, the keepers 24 are swung downwardly against the bottom of the crate, the top section C is lifted upwardly thus swinging the end sections A outwardly until they are in upright 30 position. The side sections B are now swung downwardly against the upwardly extending portions of the bottom section D. The partition F is swung upwardly until parallel with the end sections A in which position 35 it is held by the spring locking member 15. The partition F holds the side sections B downwardly and consequently the crate is maintained in its set up or operative position. When the crate has been filled, the 40 gate E is closed and fastened in that position in the manner described.

It will be noted that the removable closure 14 has a triple function. It serves as a closure, as a means of holding the gate 45 closed, and as a means when engaged by the U-shaped keepers 24 of holding the crate in its collapsed condition. In Fig. 8, I have shown the top section 30 of a modified form of the device. The top section 30 is made 50 up of slats as shown and is adapted for use without a gate. A removable closure 31 is provided and is operated in the same manner as the removable closure 14 in the device shown in Fig. 1. In Fig. 9 I have 55 shown the top section 33 of a modified form of the device. In this form, the device is made up in the form of a box. A removable closure 34 is provided and is operated in the usual manner. In this construction, 60 slots 35 are provided to receive the sides of the U-shaped keepers (not shown) when the device is in knock down or collapsed condition.

It is obvious that my invention is not restricted to the form shown in the accompanying drawings but that various changes 65 may be made without departing from the spirit and scope of the invention. The device is strong and durable in construction, light in weight, and may be manufactured 70 cheaply. Several kinds of merchandise may be transported in the same crate without being brought into contact with each other. The device may be set up or collapsed 75 quickly and easily. In its collapsed position, it occupies a relatively small space and may be stored away in tiers.

It will be noted that a longitudinal plate 3' is secured to the inner lower edge of each upper portion 1 of the end sections A. The 80 plates 3' cover the hinged connections between the upper portions 1 and the lower portions 2 of the end sections A and strengthen the latter when the crate is in its set up condition.

I claim:

1. A collapsible crate comprising a top, a removable closure slidably disposed in said top, a bottom, collapsible ends hingedly connected to said top and said bottom and folding inwardly to permit the crate to be collapsed, sides hingedly connected at their upper longitudinal edges to said top to permit the former being swung upwardly into parallel alignment with said top and said bottom, a transverse partition hingedly connected to said bottom and normally maintained in upright position to hold said sides in operative position, a locking member carried by said top to maintain said partition 100 in upright position, and U-shaped keepers hingedly secured to said bottom and adapted to receive the slidably disposed closure in said top to hold the crate in collapsed condition.

2. A collapsible crate comprising a top, a gate hingedly secured thereon, a removable closure slidably disposed in said top and said gate to hold the latter in closed position, a bottom, collapsible ends hingedly connected 110 to said top and said bottom and folding inwardly to permit the crate to be collapsed, sides hingedly connected at their upper longitudinal edges to said top to permit the former being swung upwardly into parallel 115 alignment with said top and said bottom, a transverse partition hingedly connected to said bottom and normally maintained in upright position to hold said sides in operative position, a locking member carried by 120 said top to maintain said partition in upright position, and U-shaped keepers hingedly secured to said bottom and adapted to receive the slidably disposed closure in said top to hold the crate in collapsed condition.

JACOB L. WEBER.
